CLAIM

The ornamental design for a fiber-filled lumbar support pillow, as shown and described.

DESCRIPTION

FIG. 1 is a perspective view of a first embodiment of my new design for a fiber-filled lumbar support pillow formed by a fiber-filled fabric pillow with stitching to form a center spine section;

FIG. 2 is a front elevation view of the article shown in FIG. 1, and to which the rear elevation view is the same.

FIG. 3 is a left side view of the article shown in FIG. 1, and to which the right side view is the same;

FIG. 4 is a bottom view of the article shown in FIG. 1;

FIG. 5 is a top view of the article shown in FIG. 1;

FIG. 6 is a view showing the article in use by a seated person (in phantom lines)

FIG. 7 is a perspective view of a second embodiment of my new design for a fiber-filled lumbar support pillow;

FIG. 8 is a front elevation view of the article shown in FIG. 7, and to which the rear elevation view is the same.

FIG. 9 is a left side view of the article shown in FIG. 7, and to which the right side view is the same;

FIG. 10 is a bottom view of the article shown in FIG. 7;

FIG. 11 is a top view of the article shown in FIG. 7; and,

FIG. 12 is a view showing the article in use by a seated person (in phantom lines).

The broken lines showing the human figure in FIGS. 6 and 12 are for environmental purposes only and form no part of the claimed design. The broken lines shown on the pillow are stitching.
